FENCE POST TOP

Harvey H. Ross, Detroit, Mich.

Application January 23, 1958, Serial No. 49,376

Term of patent 14 years

(Cl. D28—1)

FIG.1.

FIG.2.

FIG.5.

FIG.3.

FIG.4.

Fig. 1 is a front view in elevation of a fence post top showing my new design;

Fig. 2 is a right side view in elevation thereof, the left side being substantially the same;

Fig. 3 is a top plan view;

Fig. 4 is a sectional view on line 4—4 of Fig. 1; and, Fig. 5 is an enlarged fragmentary sectional view on line 5—5 of Fig. 1.

I claim:

The ornamental design for a fence post top, as shown and described.
